UNITED STATES PATENT OFFICE

2,656,990

EXPANSIBLE CORE FOR GLASS FILAMENT WINDINGS

Adelbert C. Radtke, Oak Park, Ill., assignor to
International Harvester Company, a corpora-
tion of New Jersey

Application November 18, 1950, Serial No. 196,479

7 Claims. (Cl. 242—72)

1

This invention relates to a new and improved expandible core for glass filament windings.

The present invention is directed to an apparatus for receiving glass filament windings in the manner of the device as shown for example in the patent to Games Slayter 2,457,786 dated December 28, 1948.

Devices of this type employ an expanding mandrel or collet over which is carried a paper sleeve for receiving windings of glass or other filaments. A continuous plurality of glass filaments are drawn from a glass furnace and are wound onto the paper core. The glass filaments being drawn will be attenuated, and in view of the intermittently disposed expanding members 15 of the mandrel the flexible paper sleeve or core upon which the glass filaments are drawn creates a plurality of alternate peaks or valleys around the circumference of the paper core. The glass filaments are wound under greater pressure at the mandrel peaks and are thus drawn more finely at these points, with the result the glass filament does not have a uniform strength 20 throughout its length but rather is weakened at the points which were positioned on the peaks 25 of the expanding mandrel.

Oftentimes glass filaments have coatings applied thereto after the glass filaments leave the forming die and the expanding mandrels of the winding tubes tend to cause fusion of the coated filaments at the several peak pressure points 30 around the periphery thereof. This, of course, makes removal of the coated strand from the spool extremely difficult.

A principal object of the present invention is to provide an expandible core for expanding mandrels presenting a substantially uniform fixed surface throughout the entire circumference to provide for uniformly tensioned glass or other filaments which may be wound thereon and a minimum of fusion of adjacent convolutions.

An important object of this invention is the provision of an expanding core for the winding tube of a continuous glass filament wherein the core has a balanced rotational inertia.

Another object of this invention is to supply an expandible metal sleeve for association with an expanding mandrel to receive filament windings, the sleeve having a spirally disposed slot formed by adjacent ends of the sleeve with spaced apertures diametrically disposed with respect to the spiral slot to accomplish rotational balance of the sleeve.

Another and further important object of this invention is to provide an expandible metal sleeve having its adjoining edges with alternate projections and recesses whereby there is an interfitting of the adjoining edges of the sleeve.

Other and further important objects of this invention will become apparent from the disclos-

2

ures in the following specification and accompanying drawings.

In the drawings:

Fig. 1 is a sectional view of an expanding mandrel with the expandible sleeve of this invention mounted thereover.

Fig. 2 is a perspective view of the expanding metal sleeve of this invention.

Fig. 3 is a perspective view showing a modified form of expanding metal sleeve.

Fig. 4 is another perspective view showing a still further modified form of expandible metal sleeve.

As shown in the drawings:

The reference numeral 10 indicates generally an expanding mandrel or collet mounted on a shaft 11 for rotation therewith. The mandrel 10 is provided with a disk-like portion 12 having radially extending slots 13 projecting inwardly 20 from the outer edge of the disk 12. The slots are regularly spaced around the periphery of the disk 12 and limit arcuate swinging movement of blades 14 which are pivotally attached at 15 on the disk 12. The outer portions of the plurality of blades 14 are rounded as shown at 16, and the expanding mandrel 10 comprises the plurality of blades 14 with their outer rounded ends 16 which move radially outwardly by centrifugal force occasioned by rotation of the shaft 11 and thus also the mandrel 10.

An expandible metal sleeve 17 is adapted to fit over the outer rounded edges 16 of the blades 14. The sleeve 17 is made from a sheet metal preferably a steel having spring characteristics. The sheet steel is shaped in a parallelogram with a ends to be rolled up cut on a diagonal so that when it is rolled into a sleeve of tubular shape there is provided a spiral slot or path 18 defined by the adjoining side edges 19 and 20. As the 35 mandrel blades 14 swing outwardly the tube 17 expands by a spreading of the spiral path 18. A plurality of regularly spaced apertures 21 are provided in a spiral path diametrically opposed to the spiral slot 18. The purpose of the apertures 40 21 is to provide a lightening of the metal tube 17 along a path which is diametrically disposed with respect to the spiral slot 18. The amount of metal removed from the apertures 21 thus compensates for the space between the adjoining 45 spiral edges 19 and 20 with the result that the sleeve 17 has a balanced rotation inertia. It should, of course, be obvious that the metal lightening means may take forms other than apertures such as shown at 21, and it is essential 50 only that the distribution of weight be balanced around the circumference of the cylindrical sleeve 17. The purpose of the spiral path 18 in deference to a straight transverse slot insures that 55 the filament which is wound on the core will be 60

3

evenly attenuated without undue strains or pressure points.

In operation, the expanding mandrel 10 is idle when the expansible metal sleeve 17 is applied over the radially extending blade members 14. A paper core or spool 22 is then applied over the metal sleeve 17 and thereafter the shaft 11 and the mandrel 10 are rotated. The rounded ends 16 of the swinging blades 14 are thrown radially outwardly by reason of the centrifugal force occasioned by rotation and there is a tendency for the edges 19 and 20 of the rolled tube 17 to spread. The spiral disposition of the path 18 and the balancing of the expansible sleeve by reason of the apertures 21 minimize undue strain on the paper core throughout any localized area thereof. The paper core 22 thus presents a smooth unbroken surface about which an endless filament such as glass as shown at 23 in Fig. 1 may be wound.

Fig. 3 shows a spring steel tube 24 having a generally spiral path 25 formed by reason of the adjoining edges 26 and 27 of the side edges of the rolled tube and similarly employs counter-balancing apertures 28 in a spiral path which is diametrically opposed to the spiral path 25 defined by the adjacent edges of the cylindrical sleeve 24. Thus the tubes 17 and 24 are substantially identical but for the adjoining edges of the sheet steel being provided with alternate projections and recesses which are alternately disposed on the edges 26 and 27 so that there is an interfitting of a projection with an oppositely disposed recess. As shown in Fig. 3, a projection 29 on the edge 26 mates with a recess or depression 30 on the edge 27. Similarly, a recess 31 on the edge 26 mates with a projection 32 on the edge 27. The projections and recesses, as shown in Fig. 3, are in the form of smoothly curved scallops. The operation of the tube 24 is identical with that of the tube 17 but further insures maximum expansibility without a complete separation of the adjoining edges 26 and 27 and thus preventing a collapse of the paper core 22 fitting over the top of the expansible metal sleeve.

Fig. 4 similarly shows a corresponding expansible metal sleeve 33 which is similar to the previously described sleeves 17 and 24. The sleeve 33 has a generally spirally disposed path 34 defined by adjoining edges 35 and 36 which are positioned adjacent each other when the sheet steel is rolled into tubular form. Here again, the metal is lightened by means of apertures 37 diametrically opposed to the spiral path or slot 34 in order that the sleeve may have its weight distributed evenly around the periphery thereof so that it is conducive to smooth non-surfing rotation. The adjoining edges 35 and 36 have projections and recesses corresponding to the sleeve 24 shown in Fig. 3. Rather than being smooth scallops, the projections and recesses are sharply defined teeth. However, the projections 38 on the edge 35 interfit with oppositely disposed recesses 39 in the edge 36, and the recess 40 of the edge 35 interfit with projections of the edge 36, thus being similar to the interfitting projections and recesses of the sleeve 24. The function of the interfitting projections and recesses is identical to that of the projections and recesses of the sleeve 24 wherein a separation of the adjoining edges 35 and 36 upon expansion of the blades 14 of the mandrel 10, although increasing the width of the generally spiral path 24, will not cause a complete separation of the edges 35 and 36.

It will thus be apparent that herein is provided

4

expansible sleeve means for operation in conjunction with expanding mandrels upon which glass or other filaments are wound with a substantially constant tension throughout. Various details of construction may be varied throughout a wide range without departing from the principles disclosed herein, and I therefore do not propose limiting the patent granted hereon otherwise than as necessitated by the appended claims.

What is claimed is:

1. An expansible core for receiving windings of filaments comprising a metal sheet formed as a sleeve in a cylindrical shape, said sleeve defining a smooth cylindrical passage on the interior thereof, said sleeve having adjacent unattached side edges of the metal sheet extending the full length of the cylindrically shaped sleeve, and said sleeve having means diametrically opposite the adjacent unattached side edges for lightening the metal whereby the reduced weight of the sleeve at the discontinuous side edges is compensated for by the lightening of the metal on the diametrically opposite side for a balanced rotational inertia.

2. An expansible core for receiving windings of glass filaments comprising a metal sheet formed as a sleeve in a cylindrical shape, said sleeve defining a smooth cylindrical passage on the interior thereof, said sleeve having adjacent unattached side edges of the metal sheet extending the full length of the cylindrically shaped sleeve, and said sleeve having apertures at intervals along the length thereof diametrically opposite the adjacent unattached side edges whereby the reduced weight of the sleeve at the discontinuous side edges is compensated for by the apertures on the diametrically opposite side of the sleeve resulting in a rotationally balanced inertia sleeve.

3. An expansible core for receiving windings of glass filaments comprising a metal sheet formed as a sleeve in a cylindrical shape, said sleeve having adjacent unattached side edges of the metal sheet extending the length thereof, and said sleeve having apertures at intervals along the length thereof diametrically opposite the adjacent unattached side edges whereby the reduced weight of the sleeve at the discontinuous side edges is compensated for by the apertures on the diametrically opposite side of the sleeve resulting in a rotationally balanced inertia sleeve, said adjacent unattached side edges disposed in a spiral path.

4. A device as set forth in Claim 3 in which the apertures are arranged in a spiral path whereby the apertures are diametrically opposite the spiral path of the side edges.

5. A device as set forth in claim 4 in which the side edges have oppositely disposed projecting and recessed portions whereby there is an interfitting of the adjacent side edges.

6. A device as set forth in claim 5 in which the projecting and recessed portions are smoothly curved scallops.

7. A device as set forth in claim 5 in which the projecting and recessed portions are sharply defined teeth.

ADELBERT C. RADTKE.
